DESIGN FOR LEATHER

Leonard I. Friedman, New York, N. Y.

Application April 18, 1936, Serial No. 62,194

Term of patent 3½ years

To all whom it may concern:

Be it known that I, Leonard I. Friedman, a citizen of the United States of America, residing in city of New York, county of Kings, and State of New York, have invented a new, original, and ornamental Design for Leather, of which the following is a specification, reference being had to the accompanying drawing, forming part thereof.

The figure is a plan view of leather embodying my new design.

The design unit is contained between the broken lines, which unit is repeated in regular succession as indicated by the extensions beyond the unit boundaries.

I claim:

The ornamental design for leather substantially as shown and described.

LEONARD I. FRIEDMAN.
